UNITED STATES PATENT OFFICE.

ANDREW J. GRUSH, OF NIANTIC TOWNSHIP, MACON COUNTY, ASSIGNOR TO
WILLIAM W. CARSON, OF NIANTIC, ILLINOIS.

HOG-TRAP.

SPECIFICATION forming part of Letters Patent No. 236,204, dated January 4, 1881.

Application filed February 12, 1880.

To all whom it may concern:

Be it known that I, ANDREW J. GRUSH, of Niantic, Macon county, Illinois, have invented certain new and useful Improvements in Hog-
5 Traps, of which the following is a specification.

This invention relates to self-acting traps for securing and holding hogs while they are to have their noses rung or other operation
10 performed on them.

The invention will be understood from the following specification and claims, reference being had to the accompanying drawings, which form a part of this specification, and in
15 which—

Figure 1 is a perspective view of my device with the rails broken away. Fig. 2 is a vertical longitudinal section.

Similar letters of reference indicate like
20 parts in both figures.

The framing of the trap is represented by the letters I H O Q, I being the rails; H, the front platform; O, the top end beams, and Q the floor of the trap.

25 A is a door, pivoted at the top to one of the cross-beams O, and slides at the bottom in a way formed by the beads S S, placed upon a spring-treadle, G, which bears upward unless the pressure is overcome by a superior force
30 from above. The door A is controlled by the levers C D, upon the latter of which is placed a weight, K, which may be adjusted in any one of the several rests W in the lever D. The tendency of the levers C D is to keep the door

35 A closed; but this tendency is overcome by the tension of the spring-treadle G, which, by bearing against the bottom of the door when open, is sufficient to retain it thus.

To the door A is pivoted a ratchet-latch, E, which moves with the door, and when the door is closed, or even partially closed, it engages with the ratchets U on the stationary lever F, which is attached to the framing, and holds it securely.

45 The treadle G is secured by adjustable hinges R to the platform H, and rests upon the spring X, which is strong enough to keep the door A in place when open.

B is a stationary door, placed beside A at
50 the front of the trap.

In the interior of the trap, near the entrance end, is placed the treadle J. This is pivoted by means of the rod j, which passes through the rails I, or may have bearings in short journals run up from the bottom of the pen beside the treadle J, and has a connecting-rod, L, extending from a front corner backward and upward to the lever M, which is pivoted to the top framing of the trap. The lever M controls another lever, N, which bears under a projection or slot in the door P and suspends it. The door P slides up and down in a slot formed in the framing at this end of the trap.

The hog enters the trap through the door P, which is kept elevated for the purpose. 65 As he passes over upon the end J' of the treadle J the connection L M N drops the door, and escape is cut off in this direction. Advancing toward the door A, which has been kept open by the pressure exerted upon it by the spring-treadle G, he steps upon this spring-treadle and releases the door, when the levers C D and weight K force it shut, or so far shut as to catch his neck, which, by the relative and proper adjustment of parts will be protruded 70 just at this moment. The closing of the door brings the latch E into engagement with the latch F, and the door is locked. Any desired operation may then be readily performed by one person alone.

80 As the size of the hogs may differ, the treadle G may have its hinges R adjusted accordingly by being placed in any of a series of holes, T.

Having thus described my invention, I desire to claim—

1. The pivoted door A, in combination with the spring-treadle G, levers C D, and weight K, substantially as set forth.

2. The combination of the treadle G, spring X, locking-latches E F, and pivoted door A, substantially as set forth.

3. The combination of the treadle J, connections L M N, and door P, substantially as described.

ANDREW J. GRUSH.
